UNITED STATES PATENT OFFICE.

CARLOS W. JONES, OF KANSAS CITY, MISSOURI, ASSIGNOR OF ONE-HALF TO MALCOLM GALBRAITH, OF KANSAS CITY, MISSOURI.

ANESTHETIC-DISPENSING CONTAINER.

Application filed January 25, 1922. Serial No. 531,650.

To all whom it may concern:

Be it known that I, CARLOS W. JONES, a citizen of the United States, residing at Kansas City, in the county of Jackson and State 5 of Missouri, have invented certain new and useful Improvements in Anæsthetic-Dispensing Containers; and I do declare the following to be a full, clear, and exact description of the invention, such as will enable others skilled in the art to which it appertains to 10 make and use the same, reference being had to the accompanying drawings, and to the figures of reference marked thereon, which form a part of this specification.

15 This invention relates to a dispensing container, the discharge of which is provided with a dropper having a controlling valve for determining the rate of discharge of the contents of the container, the valve being 20 adapted to be manipulated so that the discharge orifice can be closed, thereby permitting fractional discharge of the contents of the container at infrequent intervals without materially affecting the condition of the 25 contents.

For example, the invention is particularly 30 applicable for use by anæsthetists in administering anæsthetics, for example, ether, to patients as the dispensing container can be caused to discharge at any given rate under the control of the anæsthetist.

35 Ether usually is put up in metal containers with discharge tubes at their ends, the discharge tubes preferably consisting of soft metal which may be easily ruptured or pierced to make the orifices through which the discharge may take place.

In practice it is difficult to control the rate 40 of discharge and unless one is quite expert, there is always danger of over-saturating the mask with manifold disadvantages and great danger to the patient. If too much ether is dropped upon the mask, paralysis of the respiratory organs is liable to occur and this 45 is more or less true in a great number of cases where ether is administered.

According to my invention, the rate of discharge can be digitally controlled by the 50 anaesthetist, the receptacle being held in the hand and the dropper-controlling element manipulated between the thumb and the index finger.

There is another very important feature of

my invention in that the container may be sealed off after each discharge. As above 55 explained, the cans now in use are provided with soft discharge orifices or tubes and the most popular container is a four ounce can. In administering the ether it frequently 60 happens that a comparatively small fraction 65 of the entire contents of the can is required. If the can is kept with the remaining contents for any appreciable time, the contents of the can will deteriorate and if used, will apparently set up toxins in the system, which 70 cause great distress to the patient, such as 75 nausea, gas pains and the like.

It is one of the purposes of my invention to maintain as nearly as practical a uniform 75 quality of the ether over a considerable 80 period of use, that is, whereas, with the ordinary container, the most volatile constituents pass off shortly after the can is opened, according to my invention, a considerable portion of these at least can be 85 retained in the can because as soon as the first application of the ether has been completed, the discharge orifice will be sealed off so that liability of deterioration of the 90 ether due to oxidation or from any other causes will be reduced to a minimum, if not wholly avoided.

Therefore, I may manipulate the dropper to cause the discharge orifice to open to varying degrees to vary the effective port area of 85 the discharge opening and thereby control the rate of discharge of the contents of the can and then quickly seal off the discharge orifice so that the contents of the can will 90 be as nearly as practicable in its original 95 condition. I, thereby, avoid the liability of the more volatile gases escaping to atmosphere and leaving only a poisonous residue in the can.

The advantages above recited will be 95 clearly apparent to physicians, surgeons, anæsthetists and the like.

In order to convey a proper conception of my invention, I have illustrated one form 100 of the device in the accompanying drawings, in which

Fig. 1 is a perspective view of a dispensing container constructed in accordance with my invention.

Fig. 2 is a fragmentary side view of the 105 container, parts being broken away to show

the dispensing stopper or dropper in longitudinal section.

Fig. 3 is a disassociated view of the dropper controller and the dropper tube, parts 5 of each being shown in section, and

Fig. 4 is a bottom end view of the controller, showing the valve carried thereby.

The receptacle 1 may partake of any appropriate form but it is preferably cylindrical with a plug 2 to close an orifice 3 at one end thereof. The orifice 3 is the filling orifice and when the receptacle is filled, the plug may be secured in place by a spanner wrench or any suitable tool and for this 10 purpose I preferably cast two lugs 4 and 5 on the plug, as clearly seen in Figs. 1 and 2.

The form of plug and orifice, however, constitute no part of my invention.

20 The invention resides rather in the broad conception of providing a variable dropper which is a part of the receptacle and which has a variable effective port area to control the rate of discharge.

25 In Fig. 2 it will be seen that the dropper consists of a tube 6, one end of which extends within the receptacle and the other end without the receptacle. The inner end is closed, preferably by a plug 7 having a through 30 port or orifice 8 longitudinally thereof to communicate with the forward portion of the tube 6. The plug 7 is shown as having a valve seat 9 to receive a valve carried by the controller. The controller is shown as 35 a threaded stem 10, the exterior threads of which engage the interior threads 11 of the tube 6 so that the stem may be adjusted longitudinally of the tube to move the valve 12 to and from the seat 9. The longitudinal 40 bore or port 13 in the stem is open to atmosphere, as at 14. The other end terminates in a plurality of radial ports 15, about the valve 12 and communicating with a space 16 between the valve and the skirt portion 17 of the stem 10. The outer end of the stem 45 10 is provided with a flange or cap portion 18, the exterior of which is knurled as at 19 so that it may be easily grasped between the index finger and the thumb to manipulate 50 the stem when the can or container is held by the anæsthetist.

When the parts are properly assembled and it is desired to discharge some of the contents from the can, the cap or knurled 55 portion 19 may be digitally manipulated to unscrew the stem enough to unseat the valve 12 from the seat 9. The contents of the can may then pass through the orifice 8 into the space 16 surrounding the valve 12, through

the ports 15, through port 13 and discharge 60 from the end 14.

The first discharge will indicate whether or not the effective port area is less or more than desired and since the stem or dropper member is under direct control of the fingers, 65 the knurled portion 19 may be turned in either direction to control the effective port area so as to absolutely control the rate of discharge. Therefore, liability of flooding of the mask or excessive discharge will be 70 entirely eliminated.

Futhermore, when the proper amount of anaesthesia has been administered, the anæsthetist may turn the knurled portion 19 to screw the stem within the tube 6 so as to 75 seat the valve 12 and as this can be quickly done, liability of the highly volatile constituents of the contents of the receptacle escaping or evaporating will be entirely 80 eliminated.

I am aware that droppers have been used before and that valves have been provided in containers to vary the effective port areas and thereby the rate of discharge, but so far as I know I am the first to provide an anaesthesia-dispensing receptacle in which the rate of discharge can be positively controlled and in which the controlling means may be used to seal off the discharge orifice of the 85 receptacle.

What I claim and desire to secure by Letters Patent is:

A dispensing receptacle for administering anaesthetics comprising a container, an interiorly threaded tube carried by an extending through a wall of the container, a plug threaded into and closing the inner end of the tube, said plug having a central, through port, a frusto-conical inner face, shouldered with respect to the walls of the 95 tube to form an annulus within the tube and having a valve seat opening to the through port, and a stem threaded into the outer end of the tube, having a chambered inner end forming a valve for cooperation with said 100 valve seat and a skirt surrounding the frusto-conical portion of said plug, said stem having a port opening through its outer end and terminating short of its inner end and having a plurality of ports 105 radiating from the inner end of said main port and opening through the stem at the base of the valve, the outer end of the stem having a handle portion surrounding the 110 outer end of the tube.

In testimony whereof I affix my signature.

CARLOS W. JONES.
